UNITED STATES PATENT OFFICE.

FRED R. LARSON, OF NEW SWEDEN, MAINE.

SAFETY-ENVELOP.

1,142,444.

Specification of Letters Patent. Patented June 8, 1915.

Application filed June 12, 1914. Serial No. 844,718.

To all whom it may concern:

Be it known that I, FRED R. LARSON, a citizen of the United States, residing at New Sweden, State of Maine, have invented certain new and useful Improvements in Safety-Envelops, of which the following is a specification.

This invention relates to an envelop and the principal object of the invention is to provide improved means for preventing the envelop from being opened without detection after the envelop has once been sealed.

Another object of the invention is to provide an envelop of the character described which does not need any special construction and in which the safety device is very simple and can be applied to the envelop at a very small cost.

Another object of the invention is to so construct the envelop and safety device that it is necessary to remove the stamp in order to remove the safety attachment, thus making it very difficult to open the envelop without detection.

This invention is illustrated in the accompanying drawings, wherein—

Figure 1 is a view showing an envelop sealed and provided with the improved safety device; Fig. 2 is a sectional view taken along the line 2—2 of Fig. 1; Fig. 3 is a fragmentary view of an envelop before it is sealed; Fig. 4 is a view similar to Fig. 1 but looking at the back of the envelop; Fig. 5 is a view of the blank from which this envelop is formed.

In Fig. 5 there has been shown the blank from which this envelop is formed and from an inspection of this figure it will be seen that the envelop comprises a body portion 10 from which there extend the end flaps 11 and 12 and upper and lower side flaps 13 and 14. This envelop is very similar to the envelopes which are now used, the only difference being that the flap 11 and the upper and lower side flaps 13 and 14 are provided with openings 15, 16 and 17 which register when the envelop is sealed.

A relatively thin strip 18 is secured to the inner face of the end flap 11 and is passed through the opening 15 and then passed through the opening 17 of the flap 14 which is secured to the edges of the end flaps 11 and 12, as shown in Fig. 3. After the letter has been placed in the envelop the strip 18 is passed through the opening 16

and the upper side flap 13 is then secured to the flaps 11, 12 and 14, as shown in Fig. 1. The strip 18 is then carried across the flaps 13 and 11 as shown in this figure and stuck to the same and then bent over the edge of the envelop and stuck to the back of the same as shown in Fig. 2. This strip 18 is of such length that when in the position shown in Figs. 1, 2 and 4 the end of the strip will be covered by the stamp 19 thus making it more difficult to open the envelop without detection since in order to do so it is first necessary to remove the stamp and then the strip. Of course when the envelop is opened by the proper party the strip 18 will be torn in doing so. If an unauthorized person has opened the envelop previous to the opening of the same by the proper person the strip 18 will be torn thus indicating that the letter has been opened by persons not having authority to open the same. I have therefore provided a safety envelop which is very cheap to manufacture since the envelop does not need any special construction, it only being necessary to provide the strip 18 and to form the openings 15, 16 and 17 in the flaps 11, 13 and 14.

What is claimed is:—

1. A safety envelop comprising a body portion, end flaps carried by said body portion, upper and lower side flaps carried by said body portion, said end flaps being folded upon said body portion and said lower side flaps being folded upon said end flaps and secured thereto and being provided with an opening registering with an opening formed in one of said end flaps, a sealing strip secured to the inner face of the perforated end flap and passing through the registering openings, said upper side flaps being secured upon said end flaps and lower side flaps and provided with an opening through which said sealing strip passes, said sealing strip being extended across said upper side flap and perforated end flap and having its end portion carried around and secured to the front face of said body portion.

2. A safety envelop comprising a body portion, a wall consisting of a plurality of sections positioned in overlapping relation and provided with registering openings, a sealing strip secured to the inner face of said wall and passing through the registering openings thereof, a closure flap provided with an opening through which said sealing

strip passes when said closure flap is in a closed position, said sealing strip being extended across said envelop to the edge thereof and having its end portion carried around 5 and secured to the front face of said body portion.

In testimony whereof I affix my signature in presence of two witnesses.

FRED R. LARSON.
